JOHN SOMMER, OF PEORIA, ILLINOIS, ASSIGNOR, BY MESNE ASSIGNMENTS, TO THE UNION TRUST COMPANY, OF CLEVELAND, OHIO, A CORPORATION OF OHIO, AND JOHN A. CHAPMAN, OF CHICAGO, ILLINOIS, TRUSTEES.

STRIPPING MECHANISM FOR WIRE-DRAWING BLOCKS.

1,414,380.

Specification of Letters Patent. Patented May 2, 1922.

Application filed December 9, 1919. Serial No. 343,621.

To all whom it may concern:

Be it known that I, JOHN SOMMER, a citizen of the United States, residing at Peoria, in the county of Peoria and State of Illinois, 5 have invented new and useful Improvements in Stripping Mechanism for Wire-Drawing Blocks, of which the following is a specification.

This invention has reference to wire- 10 drawing-blocks.

The invention has for its principal object to provide a stripper for each block, whereby the coil or bundle of drawn wire may be mechanically removed from the block to a 15 reel or other support, and thereby relieve the wire-drawer or attendant of the usual physical strain in performing this work.

The invention has for a further object to provide the stripping mechanism with 20 means for securing the end of the wire rod, or wire, so that after the drawing operation, and the coiling of the wire on the block and stripper, the stripping mechanism may be removed and with it the coil or bundle 25 of drawn wire, and after the release of the coil the attached end of the wire may also be released.

That the invention may be more fully understood, reference is had to the accompanying 30 drawings forming a part of the description, in which:

Fig. 1 is a side elevation partly in section showing part of a wire-drawing-bench with one wire-drawing-block thereon and 35 my stripping mechanism associated with said block;

Fig. 2 is a view similar to Fig. 1, except that it is in full elevation and the stripping mechanism is shown removed from the 40 block, carrying with it the coil or bundle of drawn wire shown in dotted lines;

Fig. 3 is a view in elevation showing a reel and the stripping mechanism in position thereon discharging a coil or bundle 45 of drawn wire on to the reel, the stripping mechanism being partly in section;

Fig. 4 is a cross-section in plan of a wire-drawing-block as the same would appear if taken on the line 4-4 of Fig. 2, and

50 Fig. 5 is a cross-section in plan of the stripping mechanism as the same would appear if taken on the line 5-5 of Fig. 3, and

Fig. 6 is a perspective view showing the

rod, or wire gripping means secured to the inner wall of the shell or casing. 55

Like characters of reference denote corresponding parts throughout the figures.

It has been and is the general practise when drawing wire from wire rods to provide a wire-drawing-bench having operatively mounted thereon a plurality of spaced 60 rotating wire-drawing-blocks. To reduce a bundle of wire rods to any given size or sizes of wire, a bundle of rods is placed upon a suitable support, or reel, with the end 65 of the rod passing through suitable dies and attached by some suitable gripping means to the drawing-block, so that when the drawing-block is rotated the rod is drawn through the dies reducing it, and the reduced wire resulting from such drawing operation wound into a coil or bundle on the drawing-block. After the first reduction of the bundle of wire rods, to a coil or bundle 70 of wire, it is the customary practise for the wire-drawer or attendant to manually lift the drawn coil or bundle of wire from the drawing-block and remove it to a reel from which the wire is led through a die and to a drawing-block, in a manner somewhat 75 similar to that just previously stated, for the reduction of the wire rods to wire. This operation is continued as occasion may require to obtain the proper reduction of the wire, whether it be wire rods, or the wire 80 drawn from such rods. As the coils or bundles of wire are quite heavy it is at once apparent that considerable physical strain is placed upon the attendant and not only 85 is production thereby limited as the operation continues throughout a run, but the physical strain upon the attendant is a drain upon his resources which my invention eliminates.

It is the aim with the use of my stripping 95 mechanism to relieve the wire-drawer or attendant of the physical strain of removing the drawn wire in coils or bundles from the drawing-blocks, and to provide for mechanically removing the same which will speed up 100 production, and the attendant is thereby enabled to operate faster as it facilitates his handling two or more drawing-blocks at a time. This is accomplished by providing a stripping mechanism embodying a means to 105 secure the end of a wire rod, or wire to said

stripping mechanism, in place of having the securing or attaching means for the rod, or wire, directly on the drawing-block, and which fits the drawing-block and around 5 which the wire is coiled as it is drawn on the drawing-block. After the drawing operation has been completed the stripper may be removed, lifting with it the coil or bundle of drawn wire, and the same moved to a reel.

10 In the use of the invention it is contemplated that any suitable crane may be employed operated pneumatically, or in any other suitable manner under convenient control by the wire-drawer or attendant for the removal of 15 the stripping mechanism and the coil or bundle of drawn wire.

1 designates the wire-drawing-bench, table or platform on the front of which is shown the conventional controlling means 1^a for the 20 drawing-blocks. On said bench is rotatably mounted a wire-drawing-block 2. This bench may be of the usual construction and therefore need not be detailed, and the wire-drawing-block being also of the usual construction, except as hereinafter noted, and the mechanism or means employed to rotate the block as well as the controlling means being also of the usual and ordinary construction, need not be further detailed. It 30 is of course understood that the drawing-bench may be as long as required for the purpose of supporting as many wire-drawing-blocks necessary for any particular mill under consideration, and while I have 35 only shown one wire-drawing-block with my stripping mechanism applied thereto, it will become apparent that such stripping mechanism is applicable and is intended for use on all of the blocks on the bench.

40 The wire-drawing-block 2 is provided with a plurality of vertically disposed recesses 3 which open out of the peripheral face of the block and where there are only four recesses, as shown in this instance, each pair of 45 recesses are arranged diametrically opposite each other. It will be observed by reference to Figs. 1 and 2, that such recesses 3 extend vertically in the side of the block and that the base of such recesses extend approximately at right-angles to the length thereof and the recesses are so formed as to receive hooks 4 which conform in shape to the recesses 3, and when located within the recesses 50 the outer faces of the hooks are flush with the peripheral face of the block.

The stripping mechanism to which I have heretofore made reference, includes the plurality of hooks 4, with associated operating means to be described, and a cylindrical shell 60 or casing 5, which, when in operative position, as best seen in Fig. 1, rests upon the block and extends thereabove forming a continuation of said block.

The hooks 4, are preferably bent inwardly 65 and upwardly as at 6, so as to enter the cy-

lindrical shell or casing 5 and extending up into said shell or casing are pivoted at 7 between and to the spaced bars 8 (see Fig. 5) secured to the wall of the shell or casing. The bent portion 6 of the hooks in addition 70 to permitting them to enter the shell or casing 5, makes it possible to reduce the size of the shell or casing and the inclined edges of the bent portion of said hooks permit the coils of the wire riding up and around the drawing-block and hooks to ride over the bent portions of said hooks and rest thereon, otherwise if the hooks extend straight up and the shell or casing 5 was of the same 75 diameter of the main body of the drawing-block as the wire was coiled on the drawing-block it might have a tendency to raise and slip off of the top end of the block; but with the construction shown and a seat being provided for the coils any such tendency is overcome. Pivotaly connected to each hook 4 within the shell or casing 5 are a pair of links 9 which extend radially inwardly from the hooks toward the center of the shell or casing, and at their inner ends these links 9 80 are pivotally connected to a head 10 connected with a short vertical stem or rod 11 which passes up through a cross-head or frame-work 12 secured to the wall of the casing. The arrangement of the head 10 and 85 the links 9, pivotally connected, as shown, with the hooks 4, provides a toggle connection permitting the hooks 4 to be drawn inwardly, or collapsed, after the stripping mechanism has been removed from the wire-drawing-block, and thereby release the hooks 4 from the coil or bundle of wire, in the 90 manner shown in Fig. 3.

At a suitable point the wall of the shell or casing 5 is provided with a hole or perforation 13 through which the end of a wire rod, or wire is inserted, from the outside of the shell or casing 5, and the end of the said rod, or wire secured to a suitable gripping means, to insure the rod or wire being drawn through the die as the drawing-block is rotated, and the drawn wire wound or coiled on the said drawing-block, and said stripping mechanism. There are various forms of grippers which could be employed 105 for this purpose. While it is practical to employ a stripping mechanism with the gripper, for securing the rod, or wire connected with the drawing-block, I prefer to have this gripper associated directly with 110 the stripping mechanism, because then when the stripping mechanism is removed, the coil or bundle of wire may also be removed with it from the drawing-block, without having first to disconnect the end of the wire from 115 the gripper, which may be disconnected after the stripping mechanism and coil of drawn wire has been removed to the reel, and the wire deposited on the reel. This gripper is best seen in plan in Fig. 5, and in perspective 120

in Fig. 6, and includes preferably a block 14 secured to the inner wall of the shell or casing 5, coincident with the hole or perforation 13. Pivotaly arranged in said block 14 is a gripping member 15, which co-acts with a wall 16 of the block 14 to frictionally impinge the rod, or wire after it has been inserted through the opening or perforation 13 and between the gripper 15 and the co-acting wall 16. The outer end of the gripping member 15 is normally held raised by a spring 17 and said gripper 15 may be depressed to impinge upon the wire by means of the rod 18 which bears against the outer end of the gripping member 15, and has a threaded relation with a nut 19. The upper outer end of said rod 18 passes through a bearing 20 and has the crank 21 connected thereto forming a hand hold, or grip for the operator whereby he may turn the rod 18 causing the gripper 15 to impinge upon the wire, or to release it and permit the spring 17 to remove the gripper from impinging relation with the wire.

25 In Fig. 1 I have shown the stripping mechanism on the block 2 with the hooks 4 lying in the recesses 3 within the block, and with the links 9 and the head 10 in their normal position within the shell or casing 5. I 30 have also shown in this figure a rod, or wire A, in dotted lines, connected with the gripper, not shown, and the coil partially formed on the drawing-block.

To the head or top end of the shell or casing 5 there is secured in a permanent position a bail 22 to receive the hook B which is one of the elements used in connection with the crane, or other lifting means, not shown, by means of which the stripping 40 mechanism together with a drawn coil or bundle of wire is removed from the drawing-block.

In operation the rod, or wire A, shown in dotted lines, except in Fig. 6, is led from the 45 coil or bundle through a die, not shown, and thence through the hole or perforation 13 in the shell or casing 5 and secured by the gripper as previously explained, and as shown in Fig. 6. In Fig. 1 it is illustrated 50 how the coils after they are formed on the block and stripping mechanism are wound around the drawing-block and the hooks 4 lying within the recesses of said drawing-block. As the coil of wire grows in size, resulting 55 from the drawing operation, the coils extend up and around the hooks of the stripping mechanism, and the body of the shell or casing 5, as shown in dotted lines, in Fig. 2. After this drawing operation the 60 crane or other mechanical means employed for removing the stripping mechanism and the drawn coil or bundle of wire is moved to a position so that the hook B is caused to engage the bail 22 (see Figs. 2 and 3) and as 65 the hook B is lifted the drawn coil or bun-

dle of wire may also be lifted from the drawing-block, as shown in Fig. 2. In this position with the coil or bundle of wire resting upon the hooked ends and bent portions of the hooks 4 will maintain the hooks 70 in their normal retaining position until the hooks are withdrawn, in a manner which I will now explain to permit the removal of the coil or bundle of wire from the stripping mechanism. 75

I have previously stated that the coil or bundle of drawn wire is taken from the drawing-block and placed upon a reel in which case it is the intention to reduce the drawn coil or bundle of wire to a smaller 80 gauge, than that previously drawn.

In Fig. 3 I have shown a reel C which may be of the usual construction used in wire-drawing mills, except that I have provided the reel with the cone-shaped extension D from the upper end thereof for purposes which will become apparent. These reels are usually located on the floor of the mill adjacent to the drawing-bench to receive the coils or bundles of drawn wire. 90

The attendant, when the stripping mechanism with the coil or bundle of wire has been removed from the drawing-block, as shown in Fig. 2, swings the stripping mechanism to a position above the reel C and deposits the same thereabove, as shown in Fig. 3, when the same is lowered until the cone-shaped extension D engages with the block 10. A further lowering of the stripping mechanism lifts the block 10 by reason of 100 its contact with the cone-shaped extension D, which operation, draws in the links 9, collapsing the frame releasing the lower ends of the hooks 4 from the coil or bundle of wire permitting it to be deposited on the 105 base of the reel, as shown in dotted lines in Fig. 3. When the coil or bundle is so deposited on the reel, then the wire-drawer, or attendant will actuate the rod 18 to release the gripper 15, and permit the end of 110 the wire A to be detached from the stripping mechanism. This operation completed the mechanism of the crane is set into motion which will lift the stripping mechanism off of the reel C permitting the block 115 10 to drop by weight of gravity and assume the position shown in Fig. 1, with the hooks 4 moved outwardly, ready to again become seated in the recesses 3 of the drawing-block 2 upon again placing the stripping mechanism on said drawing-block. 120

What I claim is:—

1. In a device of the character described, in combination, a wire-drawing-block, and a stripping mechanism including means for 125 removing a coil of drawn wire from the block, said coil removing means releasable from the coil by contact with and pressure of a coil receiving means.

2. In a device of the character described, 130

- in combination, a wire-drawing-block, a stripping mechanism including means for removing a coil of drawn wire from the block, said coil removing means releasable from the 5 coil by contact with and pressure of a coil receiving means, and a wire gripping means connected with said stripping mechanism.
3. A stripper for a wire drawing block, including a frame, a plurality of coil sup- 10 porting members pivoted to and depending from said frame, a member movable axially in the frame, and links connecting said sup- porting members and last mentioned mem- ber, said axially movable member arranged 15 to actuate said supporting members to re- lease a coil of wire when brought into con- tact with and operated by pressure from a coil receiving means.
4. A stripper for a wire drawing block, 20 including a cylindrical casing, a plurality of coil supporting members pivoted to the cas- ing interiorly thereof and in supporting position lying next adjacent the casing and protruding from said casing and extending 25 laterally beyond the vertical plane thereof, a member supported to move axially within said casing, and means connecting said sup-

porting members with said axially movable member, said axially movable member as- suming its lower most position when said 30 supporting members are lying next adjacent said casing, and movable to its uppermost position to actuate and withdraw said sup- porting members when brought into contact with and operated by pressure from a coil 35 receiving means.

5. A stripper for a wire drawing block, including a frame, a plurality of pivotally suspended coil supporting members, and means to actuate said members to withdraw 40 the same within the frame and release the coil, only upon bringing said actuating means into contact with and resting the same upon a coil receiving means.

6. A stripper for a drawing block, in- 45 cluding a frame, and collapsible coil sup- porting members on said frame, said mem- bers arranged to normally and automatically assume coil receiving position, and auto- matically releasable from the coil when the 50 frame is deposited on and by pressure from a coil receiving means.

JOHN SOMMER.
